PHOTOGRAPHIC FILM TREATING
APPARATUS

Albert S. Howell, Chicago, Ill., assignor to The
Bell & Howell Company, Chicago, Ill., a corpo-
ration of Illinois

Application February 21, 1935, Serial No. 7,599

3 Claims. (Cl. 95—94)

My invention relates particularly to the development of motion picture film strip although not limited to development alone.

The main object of the invention resides in the provision of a novel apparatus whereby photographic film, such as motion picture film strip, is treated, say for development thereof, with a view toward the provision of an effective and convenient apparatus which includes means for effectively circulating the film treating or developing fluid and which is particularly adapted for the development of motion picture film strip.

The invention will be better understood by reference to the accompanying drawings in which—

15 Figure 1 is a vertically condensed transverse vertical sectional view of a motion picture film strip developing tank embodying apparatus of my invention;

20 Figure 2 is a vertically condensed partial sectional view substantially on the line 2—2 of Figure 1; and

Figure 3 is a vertically condensed partial elevation similar to Figure 1 with parts broken away and shown in section.

25 Referring to the drawings, a developing tank is designated at 1 and projecting downwardly from an overhead support in central relation with the tank, is a support rod 2 on the lower end of which is attached a horizontal cross bar 3. See Figure 1. Two parallel vertical pipes 4 and 5 are secured to the cross bar, as designated at 6, and project downwardly therefrom, the upper ends of these pipes being closed by the securing means 6 and the lower ends of these pipes being closed by plugs 7 screw-threaded into the lower ends thereof as shown in Figure 3.

Secured on the lower end of the pipe 4 is a bracket 8, and secured on the lower end of the pipe 5 is a bracket 9 to which is secured another bracket 10 by a securing structure designated generally at 11. The bracket 8 is provided with a bored boss 12 and the bracket 10 is provided with a bored boss 13 aligned with the boss 12, and a revolvably horizontal shaft 14 is journaled in the bores of the bosses 12 and 13. See Figures 1, 2 and 3.

T fittings 15 are secured on the pipes 4 and 5 adjacent their upper ends, and a horizontal shaft 16 extends across between and is mounted on the fittings 15. A series of flanged rollers 17 is rotatably mounted on the shaft 16 between the fittings 15, and a second series of flanged rollers 18 are fixed on the shaft 14 to be driven thereby.

A hollow vertical shaft 19 is journaled adjacent its lower end in a bored boss 21 on the bracket 9 and is journaled adjacent its upper end in a bored extension 22 of the cross bar 3, and this shaft is connected with the shaft 14 to drive the same by means of a bevel gear 23 secured on the lower end of the shaft 19 and meshing with a bevel gear 24 secured on the adjacent end of the shaft 14.

A downwardly extending shaft 25 is engaged for sliding movement in the bore of the shaft 19 and is angularly fixed therewith in a usual manner for driving the shaft 19 from an overhead point to drive the rollers 18.

As usual, the rod 2 is supported above the tank 1 by a usual elevating mechanism, not shown, for vertical movement of the cross bar 3 and the assembly carried thereby into and out of the tank 1 for the purpose of convenience particularly in lacing film 26 on the rollers 17 and 18, see Figures 1 and 2, the shaft 25 being also as usual, suspended and driven from above the tank and the sliding connection between the shafts 19 and 25 accommodating for vertical movement of the shaft 19. The film 26 is fed to and from the outer rollers 17 and 18 as shown in Figure 2 and is alternately trained over the rollers 17 and 18, as indicated in Figure 1, the film being driven at a constant speed to provide a uniform period of immersion of the film in photographic treating fluid container in the tank 1.

Two T fittings 27 are secured on the pipe 4, one adjacent the upper end and one adjacent the lower end of this pipe, and screwthreaded into hollow lateral portions of these fittings are lateral circulation opening pipes 28 forming branches of the pipe 4 and disposed between the stretches of the film 26 trained over the rollers 17 and 18, the pipe 4 being provided with lateral apertures 29 aligned with the pipes 28 to provide communication between the pipe 4 and the pipes 28. See Figures 1, 2 and 3.

The end of the upper pipe 28 adjacent the pipe 4 is sealed and supported by engagement thereof in the hollow lateral portion of a T fitting 30 secured on the pipe 5, and the corresponding end of the lower pipe 28 is sealed and supported by engagement thereof in a bored part 31 forming a part of the securing means 11.

Three T fittings 32 are secured in spaced relation on the pipe 5 between the fitting 30 and the bracket 9, and screwthreaded into the hollow lateral portions of these fittings are lateral circulation opening pipes 33 forming branches of the pipe 5 and disposed between the stretches

of the film 26 trained over the rollers 17 and 18, the pipe 5 being provided with lateral apertures 34 alined with the pipes 33 to provide communication between the pipe 5 and the pipes 33. The ends of the pipes 33 adjacent the pipe 4 are sealed and supported by engagement thereof in the hollow lateral portions of T fittings 35 secured on the pipe 4.

The pipes 33 are each provided with a longitudinally extending row of restricted circulation apertures 36, the apertures of one pipe facing one series of stretches of the film between the rollers 17 and 18 and the other facing the other series of stretches of the film between these rollers.

The pipes 33 are each provided with two longitudinally extending rows of restricted circulation apertures 37 which are arranged on opposite sides of each of these pipes so that one row faces one series of stretches of the film between the rollers 17 and 18 and the other faces the other series of stretches of the film between these rollers.

Each of the pipes 4 and 5 is provided with a branch fitting 38 secured thereon and provided with an angled passage 39, see Figures 1 and 2, which communicates with the pipe through a lateral aperture 40 in the pipe. A nipple 41 is screwthreaded downwardly into each fitting 38 in communication with the passage for engagement with a flexible pipe such as a rubber hose, designated at 42 in Figure 2, for communicating each of the pipes 4 and 5 with a suitable circulating system.

From the above it will be seen that a unit is

formed of the circulation pipe structure and the film path defining means which is supported on the circulation pipe structure, the advantages of which are obvious, the entire unit being supported from the support rod 2 for movement 5 into and out of the tank.

Having thus described my invention, I do not wish to be limited to the precise details described as changes may be readily made without departing from the spirit of my invention, but having 10 thus described my invention, I claim as new and desire to secure by Letters Patent the following:

1. In a photographic treating apparatus the combination with means defining a film strip path comprising two spaced series of revolvable 15 rollers, of a circulation pipe means forming a support for said rollers and extending between said two series of rollers and provided with a lateral branch between said two series of rollers, said lateral branch being perforated therealong. 20

2. In a photographic treating apparatus the combination with means defining a film strip path, of outlet and inlet circulation pipes extending adjacent said path and provided with perforations therealong. 25

3. In a photographic treating apparatus the combination with means defining a film strip path comprising two spaced series of revolvable rollers, of spaced outlet and inlet circulation pipes forming a support for said rollers and extending 30 between said two series of rollers and provided with lateral branches spaced longitudinally thereof, said lateral branches having perforations therealong. 30

ALBERT S. HOWELL. 35
